UNITED STATES PATENT OFFICE.

ARTHUR BRUCE SPERRY, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC TELEPHONE SYSTEM.

1,242,384.

Specification of Letters Patent.

Patented Oct. 9, 1917.

Application filed January 14, 1916. Serial No. 72,139.

To all whom it may concern:

Be it known that I, ARTHUR BRUCE SPERRY, a citizen of the United States, residing at New York, in the county of New York and State of New York, have invented 5 certain new and useful Improvements in Automatic Telephone Systems, of which the following is a full, clear, concise, and exact description.

10 This invention relates to telephone systems in which the talking connections are established, in part at least, by means of automatic or electrically actuated switching mechanism.

15 The invention is directed in general toward the provision of a system of this character in which the impulses for controlling the switches used in establishing a connection, are transmitted over the third or non- 20 talking conductor of the connecting circuits, and more particularly to a system of this character in which the test for idle trunks at the selector switches employed takes place through one of the brushes in 25 the talking circuit.

In the drawings, Figures 1 and 2, with Fig. 1 at the left, diagrammatically indicate the circuits and apparatus employed with the present invention.

30 The switches employed in the present invention may be of any desired kind, in which the switch brushes are first moved to select a group of contacts and are then moved over the contacts of the group to 35 select a particular set of contacts in the selected group. A switch of this general character is shown in the patent to Keith *et al.*, No. 815,176. In the following description of the present invention, however, 40 the rotary stepping magnet will be described as operating first, that is, it is assumed that an around-and-up switch is employed in the present system instead of the up-and-around switch shown in said 45 patent. A switch of this character is shown in an application to Oscar F. Forsberg, Serial No. 6,302, filed February 5, 1915. The side switch employed in the present invention may also be of the type shown in 50 said Forsberg application. This side switch differs from the one shown in the Keith patent, principally in that its wipers may be caused to move in certain instances upon the energization instead of upon the deenergization of its controlling magnet.

At the left in Fig. 1 of the drawings, the calling line 1 is shown joined to the connecting circuit 2 by means of a line finder switch diagrammatically indicated by the brushes 3, 4 and 5. It is immaterial, however, in what manner the calling line is joined to the trunk circuit. This could as well be accomplished by means of a line or trunk finding switch or by means of a manually operated plug and jack switch, as the present invention may be as well employed in a semi-automatic telephone system as in a full automatic system. Assuming now that the line finder brushes 3, 4 and 5 are positioned on the contacts of the calling line 1 and that the side switch wipers 6, 7 and 8 have moved to position 4, the cut-off relay 9 will be energized by a circuit extending through brush 3 and wiper 6, thus cutting off the line relay 10 of the calling line. The substation circuit of line 1 being now closed at the hook-switch, current will flow from grounded battery through the right winding of impulse relay 11, wiper 7, brush 4, the left side of the calling line, 70 through the substation apparatus, back over the right side of the line, brush 5, wiper 8 and the left winding of relay 11 back to ground. Relay 11 will attract its armature completing a circuit for the slow-release 75 relay 12.

The calling subscriber will now operate his dial to send the first series of impulses. The substation sender circuit may be substantially of the character shown in patent 90 to A. E. Lundell, No. 1,148,912, issued August 3, 1915. The sender arrangement disclosed in said patent, causes a series of interruptions in the line circuit and during the time such interruptions are being sent, 95 short circuits the calling subscriber's receiver. With the first interruption in the line circuit relay 11 will be deprived of current and will retract its armature completing a circuit from battery through the rotary stepping magnet 13 and the escape magnet relay 14 in parallel and thence through the contact and right armature of relay 15, side switch wiper 16, front contact and armature of relay 12, back contact and 100 armature of relay 11 to ground. A circuit will also be provided for the relay 15, but due to the resistance 17 in series with the winding of this relay and also due to the fact that its armatures are held retracted 105 110

by a relatively heavy spring, it will not be energized during the brief periods its circuit is closed at the back contact of relay 11 during the operation of the sender. Relay 5 14 in attracting its armature completes a circuit from battery through the escape magnet 18, wiper 19 and the armature and contact of relay 14, causing the energization of the escape magnet. Relay 14 is slow to 10 release and, therefore, holds up its armature throughout the series of interruptions in its circuit caused by the subscriber's sending device. The rotary stepping magnet 13 is, however, repeatedly energized and deener- 15 gized, thus stepping the selector switch brushes 20, 21 and 22 from group to group of the trunk lines terminating at said switch.

At the termination of the series of im- 20 pulses, the circuit of relay 11 is maintained closed so that magnet 13 and relay 14 de-energize. The switch stops on the selected group of contacts, and as relay 14 retracts its armature due to the prolonged interruptions of its circuit, the escape magnet 18 25 becomes deenergized and moves the side switch wipers to position 2.

In position 2 the test relay 23 is joined to the selector brush 21 through wiper 24. A 30 circuit is also established for the test relay 23 from battery through relay 15, wiper 16, vertical off-normal contact 25, which opens on the first vertical step, and through the winding of relay 23 to ground. A circuit is 35 now closed from battery through the vertical stepping magnet 27, off-normal contact 28, wiper 29 and interrupter 30 thus causing the brushes 20, 21 and 22 to be stepped from set to set of the trunk contacts in the selected group. The test contact of busy 40 trunks will be supplied with battery potential through the brush 21, wiper 24 and resistance 26 of the selector associated with said trunk at one of its multiple terminals 45 and, therefore, the test relay will be held up while brushes 20, 21 and 22 pass over busy trunks. When they engage the contacts of an idle trunk, battery will not be present upon the contact engaged by brush 21, and 50 relay 23 will fall off closing at its left armature and back contact the circuit for the escape magnet 18. The escape magnet will be energized, and in attracting its armature will move the side switch to position 3.

55 The calling subscriber's line is now connected through to the connector switch shown in Fig. 2. If desired, however, other selector switches, similar to the one shown to the right in Fig. 1, may be interposed 60 between said selector switch and the connector switch of Fig. 2.

In the present disclosure, however, the calling subscriber will now operate his sending device to send out the next or tens series 65 of impulses, each interruption at the send-

ing device will cause the retraction of the armature of relay 11 as before. With the first retraction of the armature of relay 11, a circuit will be completed from battery through the rotary stepping magnet 101, 70 wiper 102 and from battery through the escape magnet relay 103 in parallel therewith and thence through the left armature and back contact of test relay 104, back contact and right armature of relay 105, brush 75 20, wiper 16, front contact and armature of relay 12 and the back contact and armature of relay 11 to ground. Magnet 101 and relay 103 will both be energized. A circuit will also be established for relay 105, but as 80 this relay is made slow to pull up by providing its armatures with relatively strong retractile springs, it will not be affected by the brief current impulses therethrough by the operation of the sending device. Relay 85 103 is made slow to release and holds up throughout the series of impulses thereby maintaining an energizing circuit through its armature and alternate contact for the escape magnet 106. The rotary stepping 90 magnet 101 is repeatedly energized and de-energized, due to the impulses of current therethrough, and steps the connector switch brushes 107, 108 and 109 from group to group of the subscriber's line contacts 95 terminating therein until the tens group in which the wanted line terminates is reached. The circuit for relay 11 will now be maintained closed, thus holding open the circuit for stepping magnet 101 and relay 103. Relay 103 will then retract its armature and interrupt the circuit for the escape magnet 106 causing the side switch to move to position 2.

The subscriber now operates the sending 105 device to send the final or units series of impulses. With the first retraction of the armature of impulse relay 11, circuits are closed through the vertical magnet 110 and the escape magnet relay 103 in a manner 110 similar to that in which rotary magnet 101 and relay 103 were energized when the tens series of impulses were sent. Relay 103 again closes the circuit for the escape mag- 115 net 106 and maintains said magnet energized throughout the series of impulses. Vertical stepping magnet 110 is repeatedly energized and deenergized, moving the brushes 107, 108 and 109 from set to set of the line terminal contacts of the selected 120 tens group.

When the connector switch brushes are positioned on the terminals of the called line, the calling substation circuit will remain closed at the sending device causing 125 relay 11 to hold up its armature, thus holding open the circuit of magnet 110 and relay 103. Relay 103 will retract its armature, but as its contacts are of the make-before-break character, the circuit of the escape 130

magnet 106 will be extended through the normal contacts of relay 103, test relay 104 and its normal contact, wiper 112 and brush 107 to the test contact of the wanted line.

- 5 We will first assume that the wanted line is busy, in which case the test contact will be connected to earth through brush 107 and side switch wiper 112 in positions 3 and 4 of the connector switch associated with multiple contacts of the line. This being the case, test relay 104 will attract its armature, completing a locking circuit for itself and escape magnet 106 in series through its right alternate contacts and side switch 15 wiper 113 to ground. The escape magnet will thereupon be locked up, and the side switch wipers will remain in position 2 until the switch is released and returns to its normal position.
- 20 The escape magnet 106 being energized and the side switch being in position 2, the busy tone device 114 is joined to the upper talking strand. It will be noted that this busy tone device was connected to the upper 25 talking conductor while the last series of impulses was being transmitted, but as the calling subscriber's receiver is short-circuited during the sending of the impulses and as the connector side switch moves to 30 position 3 simultaneously with the opening of this shunt circuit when the wanted subscriber's line is idle, the calling subscriber in that case would not hear the tone.

If the called line is busy, the calling subscriber will hear the busy tone, and upon replacing his receiver on the hook will open the circuit for relay 11. The armature of relay 11 will fall off and will remain retracted completing a circuit from battery 40 through the slow-to-pull-up relay 105, brush 20 and wiper 16, also from battery through the slow-to-pull-up relay 15 and resistance 17, and thence through the front contact and armature of relay 12 and back contact and armature of relay 11 to ground. As relay 45 12 is slow to release, it permits a sufficient flow of current over the circuit to energize relays 15 and 105 before it retracts its armature. Release relay 15 completes a circuit 50 from battery through the release magnet 31, rotary off-normal contact 32, closed on first rotary step, and front contact and left armature of relay 15 to ground. The release magnet attracts its armature and locks up in 55 a circuit through off-normal contact 32 and its armature and front contact, thus insuring the return of the selector switch to normal position. Relay 105 completes a circuit from battery through the release magnet 60 117, rotary off-normal contact 118, closed on first rotary step, front contact and left armature of relay 105 to ground. Magnet 117 pulls up and locks through contact 118 and its armature and contact, thus causing the 65 restoration of the connector switch.

If the wanted subscriber's line is idle, the contact engaged by brush 107 will not be connected directly to ground as previously described and, therefore, relay 104 will not be energized and magnet 106 will retract its 70 armatures moving the side switch to position 3. A circuit will now be completed from battery through the escape magnet 106, armature and contact of trip relay 119 and side switch wiper 113 to ground. The 75 escape magnet attracts its armature, and closes a circuit from generator 120 through trip relay 119, contact and right armature of magnet 106, wiper 121, brush 108, the right 80 side of the subscriber's line, through the substation bell, back over the left side of the line, brush 109 and side switch wipers 122 and 113 to ground. This causes the bell of the called substation to ring.

Upon the response of the called subscriber, the bell is short-circuited causing an increased flow of current through relay 119, which attracts its armature, thus interrupting the circuit for escape magnet 106 and causing the side switch to move to position 4. 85

The lines are now connected through for conversation. Talking battery is supplied to the calling subscriber through the windings of the impulse relay 11, and battery is supplied to the called subscriber through resistances 26 and 33.

The release of the switches is controlled solely by the calling subscriber, and when he interrupts his substation circuit by replacing his receiver upon the hook, relay 11 will 100 fall off, after which release will take place in exactly the same manner as described in regard to an unsuccessful connection.

What is claimed is:

1. In a telephone system, an electrically operated switch, a circuit extending to said switch, said circuit including a talking conductor and a non-talking conductor, means controllable over said non-talking conductor for actuating said switch in establishing a 110 connection, and test means connected to said talking conductor.

2. In a telephone system, an electrically operated switch, a connecting circuit extending to said switch, said connecting circuit comprising a pair of talking conductors and a third or non-talking conductor, means controllable over said third conductor for actuating said switch in establishing a connection, and test means connected to one 120 of said talking conductors.

3. In a telephone system, an incoming line, means including an electrically operated switch for extending said line, a connecting circuit extending to said switch, 125 said connecting circuit comprising a talking conductor and a non-talking conductor, means controllable over said non-talking conductor for actuating said switch in establishing and in disestablishing a connection.

- tion, and test means connected to one of said talking conductors.
4. In a telephone system, an incoming line, means including a selector switch for 5 extending said line, a connecting circuit extending to said switch, said circuit comprising a pair of talking conductors and a third or non-talking conductor, means controllable over said third conductor for causing 10 the movement of said switch in establishing a connection, means for determining the busy or idle condition of a circuit connected to one of said talking conductors, and means for releasing said switch controllable over 15 said third conductor.
5. In a telephone system, a subscriber's line, means including a selector switch for extending said line, a connecting circuit extending to said switch, said circuit comprising 20 a talking conductor and a non-talking conductor, a stepping magnet for said switch, means for joining said magnet to said non-talking conductor, means for transmitting impulses over said third conductor 25 to said magnet to cause the movement of said switch in establishing a connection and means for determining the busy or idle condition of a circuit arranged to be connected with said talking conductor.
- 30 6. In a telephone exchange system, a connecting circuit, including a talking conductor and a non-talking conductor, a selector switch having brushes at which said conductors respectively terminate, groups of 35 trunk lines having terminals arranged to be engaged by said brushes, means operable by impulses over said non-talking conductor for moving said brushes from group to group of said trunk line terminals, and 40 means connected to said talking conductor for controlling the operation of said switch to select the terminals of an idle trunk line.
7. In a telephone exchange system, a connecting circuit, including a talking conductor and a non-talking conductor, a switch 45 having brushes at which said conductors respectively terminate, groups of circuit terminals arranged to be engaged by said brushes, means operable over said non-talking conductor for moving said brushes from group to group of said extension circuit terminals, and means connected to said talking conductor for determining the busy or idle condition of a circuit having its terminals 55 engaged by said brushes.
8. In a telephone exchange system, a connecting circuit, comprising a pair of talking conductors and a third or non-talking conductor, a selector switch having brushes at 60 which said conductors respectively terminate, extension circuit terminals arranged in groups, means operable over said third conductor for moving said brushes to select a group of said extension circuit terminals, 65 means for causing said brushes to move from circuit to circuit in the selected group and means connected to one of said talking conductors for bringing said switch to rest in engagement with the terminals of an idle extension circuit. 70
9. In a telephone exchange system, a connecting circuit consisting of a talking conductor and a non-talking conductor, a selector switch having brushes at which said conductors respectively terminate, groups of 75 extension circuits having terminals arranged to be engaged by the brushes of said switch, means controllable over said non-talking conductor for moving said brushes from group to group of the terminals of said extension circuits, means for moving said brushes from set to set of the terminals in the selected group, a test relay, and a side switch having a wiper for joining said relay to one of said talking conductors during 80 such last named movement. 85
10. In a telephone exchange system, a connecting circuit consisting of a pair of talking conductors and a third or non-talking conductor, a selector switch having 90 brushes at which said conductors respectively terminate, groups of extension circuits having terminals arranged to be engaged by the brushes of said switch, means controllable over said third conductor for 95 moving said brushes from group to group of the terminals of said extension circuits, means for moving said brushes from set to set of the terminals in the selected group, a test relay, means for joining said relay to 100 one of said talking conductors during such last named movement and means controlled by said relay for causing said switch to stop with its brushes on the terminal contacts of an idle connecting circuit. 105
11. In a telephone exchange system, a connecting circuit consisting of a pair of talking conductors and a third or non-talking conductor, a selector switch having brushes at which said conductors respectively terminate, groups of 110 extension circuits having terminals arranged to be engaged by the brushes of said switch, means controllable over said third conductor for moving said brushes from group to group of the terminals of said extension circuits, a stepping magnet for moving said brushes from set to set of the terminals in the selected group, a side switch, a circuit for said magnet including a wiper of said side switch, a test relay, a side switch wiper for joining said relay to one of said talking conductors during such last named movement, a magnet for operating said side switch and a circuit for said side switch 115 magnet controlled by said relay. 120
12. In a telephone exchange system, a calling subscriber's line, means including a selector switch for extending said line, a connecting circuit including a pair of talk- 130

ing conductors and a third or non-talking conductor extending to said switch, groups of extension circuit terminals, an impulse relay, means at the substation for controlling the operation of said impulse relay to transmit impulses over said third conductor, an electro-magnet associated with said third conductor and arranged to be actuated by said impulses for moving said switch from group to group of said terminals, means for moving said switch over the terminals in a group, a test relay and means for connecting said relay to said talking conductors to cause said switch to stop when its brushes engage the terminals of an idle extension circuit.

In witness whereof, I hereunto subscribe my name this 13th day of January, A. D. 1916.

ARTHUR BRUCE SPERRY.
